ATTORNEY.

UNITED STATES PATENT OFFICE.

WILLIAM G. WILSON, OF WEST NEW BRIGHTON, NEW YORK.

SINK-SEAL.

1,379,501.

Specification of Letters Patent.

Patented May 24, 1921.

Application filed September 29, 1919, Serial No. 327,036. Renewed March 23, 1921. Serial No. 454,903.

To all whom it may concern:

Be it known that I, WILLIAM G. WILSON, a citizen of the United States, residing at West New Brighton, in the county of Richmond and State of New York, have invented new and useful Improvements in Sink-Seals, of which the following is a specification.

This invention relates to a cover or seal for the outlet of a sink, and has for its 10 principal object the provision of a seal having buoyant qualities, so as to uncover the outlet when free to float upon the water admitted to the sink, means being provided to hold the seal immovably positioned to 15 cover the outlet when use of a large amount of water is desired.

More specifically stated, the invention makes use of resilient means carried by the seal and constructed to frictionally engage 20 the sink for holding the seal in position to cover the outlet, the seal being further designed to permit of free movement of the seal toward and away from said outlet as the occasion may require.

25 The nature and advantages of the invention will be better understood when the following detail description is taken in connection with the accompanying drawings, the invention residing in the construction, 30 combination and arrangement of parts as claimed.

In the drawing forming part of this specification, like numerals of reference indicate similar parts in the several views and 35 wherein:—

Figure 1 is a view in elevation of the seal or cover forming the subject matter of my invention.

Fig. 2 is a vertical sectional view there- 40 through showing the manner of associating the seal or cover with the sink.

Fig. 3 is a view of the resilient member.

Referring to the drawing in detail, 10 indicates the bottom of a sink provided with 45 the usual outlet opening which establishes communication between the sink and the discharge pipe 11, the outlet opening having arranged therein the usual strainer 12.

The cover or seal for the outlet opening, 50 is indicated at 13 and may be of any desired shape or cross sectional configuration. The seal is constructed, from buoyant material, and is equipped with a gasket 14 which projects below the bottom edge of the seal or 55 cover 13 and is properly curved to effectively engage the bottom of the sink about

the outlet opening as shown in Fig. 2. By reason of the fact that the seal is constructed from buoyant material, it is obvious that the seal or cover is susceptible of movement 60 toward and away from the outlet opening when water is admitted to the sink, the seal floating upon the water as understood. With a view of maintaining the seal immovably positioned within the sink to cover 65 the outlet opening, I provide a resilient means designed to frictionally engage the sink for this purpose. As shown in this specific embodiment of the invention, the means for this purpose consists of a single 70 strand of resilient wire, or other suitable material which is bent to provide a loop disposed between the cover or seal 13. The resilient material 15 is passed through an opening centrally of the seal or cover 13 and 75 terminates to provide a finger ring 16. The limbs 17 and 18 respectively of the said loop slide through adjacent openings 19 of the strainer 12, the limb 18 having a right angularly disposed hook like portion 20, which 80 as shown by full lines in Fig. 2 is removably associated with the limb 17.

In practice, assuming the parts are arranged in the manner illustrated in Fig. 2, with the hook like portion 20 of the limb 85 18 embracing the limb 17, of said loop the parts are so disposed relatively as to permit free movement of the seal or cover 13 toward and away from the outlet opening of the sink, the seal or cover floating upon the water 90 admitted to the sink for uncovering the outlet opening as will be understood. As the water continues to run into the sink with the parts in the position stated, the seal or cover 13 will remain unseated to permit of free 95 passage of the water through the outlet opening of the sink into the pipe 11. However when it is desired to use a large quantity of water within the sink, the seal or cover 13 is elevated by engaging the finger 100 ring 16, during which operation the limbs 17 and 18 are passed through the openings 19 of the strainer. When the parts are positioned a proper distance in the sink to permit of access being had to the said limbs 105 of the loop, the limb 18 is moved in the direction of the limb 17 to disengage the hook-like portion 20 from the latter mentioned limb. Upon release of the limb 18 the latter assumes the position illustrated by dotted 110 lines in Fig. 2 when the seal or cover is placed over the outlet opening. In this

position of parts, the limb 18 frictionally engages the wall of the opening in the strainer through which it passes, to maintain the seal or cover 13 in the position shown. It is of course understood that the cover or seal 13 may be moved from engagement with the sink with the limb 18 in the position shown by dotted lines, by pulling upon the resilient element from the ring 16.

10 While I have shown and described what I consider the preferred embodiment of the invention, I desire to have it understood that I do not limit myself to the disclosure herein made, and that such changes may be 15 resorted to when desired as fall within the scope of what is claimed.

Having thus described my invention what I claim as new is:

1. A seal or cover for the outlet of a sink, 20 comprising a buoyant body normally covering said outlet, means carried by said cover and designed to engage the sink for holding the cover immovably positioned above the outlet opening, and said means being adjustable relative to the cover for permitting free movement of the cover to float upon the water admitted to the sink as described.

2. A seal or cover for the outlet of a sink, 30 comprising a buoyant body, a gasket projecting beyond the lower edge of said body, means suspended from the body and designed to engage a sink to hold the cover immovably positioned above said outlet opening, and said means being designed to assume a position free of the sink, whereby said cover is permitted free movement to float upon the water admitted to the sink.

3. A seal or cover for the outlet of a sink, 40 comprising a buoyant body normally covering said outlet, means suspended from the cover and designed to engage the sink for holding the cover immovably positioned above said outlet, said means being adjustable to assume a position free of the sink to allow the cover free movement under influence of the water admitted to the sink, and said means also serving to guide said cover in its movement.

4. A cover or seal for the outlet opening 50 of a sink, comprising a buoyant body normally seated upon the sink and surrounding said outlet, a resilient element carried by the cover and having a finger engaging portion disposed above the latter, and spaced limbs depending below the cover, said limbs

normally engaging the sink to hold the cover immovably positioned above the outlet opening, means whereby said limb is maintained spaced from the sink to permit the cover free movement to float upon the water when the latter is admitted to the sink.

5. A cover or seal for the outlet of a sink, 60 comprising a buoyant body normally seated upon the sink and surrounding said outlet, a resilient element carried by the cover and including spaced limbs depending therefrom, one of said limbs being movable toward and away from the other limb, and when separated therefrom engages the sink to hold the cover immovably positioned, 70 means for holding said limbs associated in a manner whereby said movable limb is held spaced from the sink to permit the cover free movement to float upon the water admitted to the sink.

6. A cover or seal for the outlet of a sink, 75 comprising a buoyant body, a gasket surrounding said body and projecting below the lower edge thereof, a resilient element slideable through an opening in said body and having a portion disposed above the latter, and spaced limbs depending from said body and passed through openings in the strainer of the sink, one of said limbs having a hook-like terminal removably engaged with the 80 other end for holding said limbs in a position to permit free movement of the cover toward and away from the outlet opening, said cover adapted to float upon the water admitted to the sink, and said limbs when 85 separated by the hook like terminal assuming positions to frictionally contact the strainer to hold the cover immovably positioned about the outlet opening.

7. A cover or seal for the outlet of a sink, 90 having a perforated strainer, said cover comprising a buoyant body, a resilient element depending from the body and having spaced limbs slideable through openings in the strainer, said limbs normally engaging said 100 strainer to hold the cover immovably positioned above the outlet opening, one of said limbs being movable with relation to the other, and means for holding said limbs positioned relatively to permit free movement of the cover toward and away from the outlet opening as and for the purpose specified.

In testimony whereof I affix my signature.

WILLIAM G. WILSON.
